CALCULATING MACHINE

Christopher Frederick Webb, Uxbridge, England,
assignor to Bell Punch Company Limited, London, England, a British company

Application June 15, 1939, Serial No. 279,257
In Great Britain June 25, 1938

7 Claims. (Cl. 235—144)

This invention relates to calculating machines of the key controlled multiple bank kind comprising a plurality of wheels or drums which are caused to rotate on actuation of the machine through angles dependent on the values of the figures impressed on the machine in such actuation, the said wheels or drums bearing figures visible from the exterior of the machine or alternatively forming part of so-called totaling mechanism.

In machines of this kind hitherto proposed a transfer from one wheel to the adjacent wheel of higher order produces a rapid partial rotation of the latter wheel, the said latter wheel moving into its final position at comparatively high speed. With such an arrangement special means are necessary for effecting a sudden arrest of the wheel in its final position and it is as a consequence of this sudden arrest that the well known fault of wheel overthrow sometimes occurs. Also in prior machines of the kind with which the invention is concerned, the operation of zeroising the wheels often necessitates the provision of complicated mechanism and the movement from their normal positions of a relatively large number of parts.

One object of the present invention is to provide improved means for effecting a transfer from one wheel to the adjacent wheel of higher order without the use of special arresting means and also without the possibility of overthrow occurring; a further object of the invention is to provide improved and simplified mechanism for zeroising the wheels.

The invention comprises a calculating machine in which a transfer from one wheel to the adjacent wheel of higher order is effected through the intermediary of a pin or pins engageable in a slotted wheel, the arrangement being such that the slotted wheel is brought to rest by a pin immediately before the latter disengages the slotted wheel whereby the wheel of higher order is brought to rest in its correct position at the end of the transfer operation.

Also the invention comprises the combination of a wheel spring urged in the direction opposite to that in which it is rotated during normal operation of the machine, a detent serving to hold the wheel against movement in said reverse direction when the wheel is at rest out of zero position, and a stop member or members so arranged that when the detent is withdrawn from the wheel with the latter at rest out of the zero position the wheel is rotated by the spring in the said reverse direction until it

reaches the zero position whereupon its movement is arrested, the act of withdrawing the detent representing the sole operation necessary to initiate the zeroising of the wheel.

5 The accompanying drawings illustrate one manner of applying the invention to a calculating machine of the kind comprising figure bearing wheels the figures on which are directly visible from the exterior of the machine.

10 In the drawings:

Fig. 1 is a front elevation showing a pair of figure wheels associated with transfer mechanism constructed in accordance with this invention.

15 Fig. 2 is a cross section on the line II—II Fig. 1 with certain parts broken away.

Fig. 3 is a cross section on the line III—III Fig. 1.

20 Fig. 4 is a cross section on the line IV—IV Fig. 1 showing also part of the outer casing of the machine.

Fig. 5 is a cross section on the line V—V Fig. 1 with certain parts omitted showing the so-called "duplexing" arrangement.

25 Fig. 6 is a detail plan view showing the arrangement associated with each figure wheel for enabling the machine to be used for the purpose of subtraction.

Fig. 7 is a side elevation showing the arrangement for zeroising the figure wheels.

30 It will be understood that the following description applies to the mechanism associated with one figure wheel, the parts being reproduced exactly for each of the other figure wheels 35 with the possible exception of the wheel of highest order.

Referring to the drawings each wheel 10 is 40 constructed in the form of a disc having a peripheral flange on the outer side of which are provided the figures, the wheel being rotatably mounted on a fixed spindle 11 extending transversely the entire width of the machine. Associated with each wheel is a pinion 12 also 45 rotatable on the spindle 11, this pinion being provided with as many teeth as there are figures on the wheel 10 and being arranged for engagement by a movable rack 15 (Fig. 2) serving to revolve the figure wheel. The rack 13 may be 50 actuated in any convenient manner but preferably in the manner described in my co-pending application Serial No. 275,375, filed May 24, 1939.

55 Rotatably mounted on a spindle 14 arranged parallel to the spindle 11 is a toothed wheel 15, the latter being in mesh with the pinion 12

and being provided with twice as many teeth as the pinion so as to form a 2:1 reduction gearing. The toothed wheel 15 carries on the side facing the figure wheel 10 a cam plate 16 having a riser 17 and a fall 18 situated opposite each other, and pivotally mounted on spindles 19, 20 arranged on diametrically opposite sides of the spindle 14 is a pair of double-armed levers 21, 22 and 23, 24, the said levers being subjected to the influence of a spring 25 serving to hold the ends of the arms 21 and 23 against the periphery of the cam plate 16. Rotatably mounted on a further spindle 26 is a toothed wheel 27 in mesh with the toothed wheel 15 and having as many teeth as the latter and this wheel 27 is connected by means of a coil spring 28 to a further toothed wheel 29 also rotatably mounted on the spindle 26, the spring 28 being coiled around cylindrical parts 30, 31 carried respectively by the wheels 27, 29 and having its ends connected as best shown in Fig. 1 to pins 32, 33 on the said wheels. The arrangement described is such that rotation of the pinion 12 causes rotation of the toothed wheel 27 and this in turn through the intermediary of the spring 28 tends to cause rotation of the wheel 29. Also the spring is arranged to have a certain minimum torsion when the figure wheel is in the zero position.

In mesh with the toothed wheel 29 is a further toothed wheel 34, the latter being rotatably mounted on the spindle 14 and carrying on the side facing the figure wheel 10 of lower order a stop plate 35 having a nose 36 arranged for engagement by the ends of the arms 22, 24 of the double-armed levers aforementioned under the conditions described below. On the side of the wheel 34 opposite that on which the plate 35 is situated is a pair of pins 37 arranged on diametrically opposite sides of the spindle 14, these pins being adapted to engage in the slots of a slotted wheel 38 which is connected to the pinion 12 associated with the adjacent figure wheel of higher order and is provided with as many slots as there are figures on that wheel. The wheels 29, 34 are provided with the same number of teeth and for simplicity in manufacture these wheels may be identical with the wheels 15 and 27.

Each pinion 12 is associated with a detent 39 pivotally mounted on the spindle 20 and acted upon by a spring 40 serving to hold the detent 39 in engagement with the teeth of the pinion. Each detent is also provided with an upwardly extending projection 41 arranged as shown in Fig. 7 to extend through a slot in a common yoke 42, the latter being pivotally mounted at 43 to the machine and being connected by a link 44 to a handle (not shown) at the exterior of the machine. Thus when the handle is actuated to swing the yoke 42 in a counterclockwise direction as viewed in Fig. 7 every detent 39 is lifted from engagement with its corresponding pinion.

The operation of the mechanism above described is as follows:

Figs. 1-4 show the figure wheel in the zero position with the arm 23 held by the cam plate 16 in a position wherein the arm 24 obstructs the nose 36 as shown in full lines in Fig. 3. The train of gear wheels 34, 29, 27, 15 and 12 is thus held stationary at one end of the train by the engagement of the arm 24 with the nose 36 and at the other end of the train by the engagement of the detent 39 with the pinion 12, the aforementioned minimum torsion of the spring 28 serving to

urge the nose 36 into contact with the arm 24 and the teeth of the pinion 12 against the end of the detent 39. Also the arm 21 has just passed the fall 18 and the free end of the arm 22 is situated at its greatest distance from the spindle 14. If now the rack 13 is actuated to rotate the pinion 12 clockwise in the direction of the arrow in Fig. 2 the wheels 15 and 27 will be rotated in the directions of their respective arrows thus serving to increase the torsion of the spring 28, the wheel 29 still being held stationary as a result of the engagement of the arm 24 with the nose 36. Also during such rotation of the pinion 12 the high part of the cam plate 16, i. e. the upper semicircular portion as viewed in Fig. 2, will move in contact with the arm 23 and will thus maintain the arm 24 in engagement with the nose 36 while the rising part of the cam will move past the arm 21 and cause the end of the arm 22 to move in a direction towards the spindle 14. After a single actuation of the rack 13 which will not be sufficient to rotate the pinion 12 through a complete revolution the parts will thus come to rest with the end of the arm 23 located on the high part of the cam plate at a point between the riser 17 and the fall 18 while the end of the arm 21 will be located on the low part of the cam plate between the said riser and fall. If now the rack is actuated a second time to an extent which will complete one revolution of the pinion the cam plate 16 will be rotated to move the fall 18 just past the end of the arm 23, the latter then moving sharply under the influence of the spring 25 in a direction towards the spindle 14 and causing the arm 24 to be withdrawn from the nose 36 into the position shown in interrupted lines in Fig. 3. The release of the nose 36 will then permit the wheels 34 and 29 to be rotated sharply by the spring 28 in the direction of the arrows in Fig. 3, rotation of the wheels being arrested by abutment of the nose 36 against the end of the arm 22 which is now situated in the path of the nose. The figure wheel of lowest order is thus once more in the zero position but each of the toothed wheels 15, 27, 29, 34 is now by virtue of the 2:1 reduction gearing between the pinion 12 and the wheel 15 in a position 180° removed from the positions illustrated in Figs. 1-4.

Rotation of the wheel 34 as above described through 180° will cause the lowermost pin 37 to enter a slot in the slotted wheel 38 and rotate the same in the direction of the relative arrow in Fig. 4, the figure wheel associated with the slotted wheel being thereby advanced through one digit and the pins 37 interchanging positions. With such an arrangement the slotted wheel is rapidly decelerated towards the end of its partial rotation and is eventually brought to rest positively by the pin before the latter completely releases the wheel. Hence the figure wheel to which the transfer is made is brought to rest in its correct position at the end of the transfer by the operation of the parts which are directly responsible for effecting the transfer and all possibility of overthrow of the figure wheel is avoided.

If the second actuation of the rack 13 is sufficient to rotate the figure wheel of the lower order past the zero position the transfer will take place during rotation of the figure wheel.

If now the rack 13 is actuated further to complete two revolutions of the figure wheel the arm 22 will be released from the nose 36 and the wheel 34 will be permitted to rotate through a

half-revolution until arrested by abutment of the nose 36 against the arm 24, the parts now assuming once again the positions shown in Figs. 1-4.

The operation of zeroizing the figure wheel when it is located out of zero position is effected by withdrawing the detent 39 from engagement with the pinion 12, withdrawal being effected as previously described by manipulation of the handle at the exterior of the machine. As the train of gearwheels 34, 29, 27, 15 and 12 is held stationary at one end by abutment of the nose 36 against either the arm 24 or the arm 22 and at the other end by engagement of the detent 39 with the pinion 12 withdrawal of the detent will cause the pinion 12 and the toothed wheels 15, 27 to be rotated by the spring 28 in directions opposite to the arrows in Fig. 2, such rotation being ultimately limited by abutment of the fall 18 against either the arm 21 or the arm 23. If the arm 24 happens to be arresting the nose 36 then movement of the wheel 15 will be arrested by the fall 18 striking the arm 21 whereas if the arm 22 is arresting the nose at the time of zeroising it will be the arm 23 which engages the fall 18. In either case the figure wheel will be in zero position at the instant the wheel 15 is arrested and hence when the detent is withdrawn the figure wheel will move in the reverse direction to that in which it is rotated by the rack 13, such reverse movement being arrested when the figure wheel reaches zero position. Fig. 7 shows the two positions of arrest of the fall 18 although it will be obvious that both arms 21 and 23 cannot be engaging the fall at the same time.

The construction above described thus permits the wheel to be zeroised in an extremely simple and convenient manner, the only operation necessary to initiate such zeroising being the act of withdrawing the detent from the pinion.

As is well known it is necessary in machines of the kind with which the invention is concerned to provide special so-called "duplexing" means to prevent a transfer to a figure wheel while the latter is being independently rotated, for example by its own rack or equivalent mechanism, the transfer being withheld until the said wheel has come to rest. In the example shown I provide a so-called "duplex" lever 45 (Fig. 5) pivotally mounted on a fixed spindle 46, the lower end of the lever being arranged adjacent the lower transfer pin 37 and the lever being formed at its upper end with an upwardly extending projection 47 arranged, when the parts of the machine are at rest to abut against a member 48 forming part of a system of linkages associated with the figure wheel the transfer to which is controlled by the duplex lever. The member 48 is caused to move in a vertical plane during operation of the said linkages and it may, for example, constitute the driving bar described in my aforesaid co-pending application. Also the duplex lever 45 is acted upon by a spring tending to rotate the lever in a clockwise direction as viewed in Fig. 5 and preferably the spring 40 aforementioned is used for this purpose.

When no movement is being communicated to the figure wheel the parts occupy the positions shown in full lines in Fig. 5, the lever 45 being held with its projection 47 in contact with the member 48 and its lower end out of the path of movement of the lower transfer pin 37. Under such conditions any desired number of transfers may be communicated to the figure wheel. When however the figure wheel is rotated as a result

of the actuation of a key or other member associated therewith the member 48 is moved out of the full line position shown in Fig. 5 into for example the interrupted line position thus allowing the spring 40 to rotate the duplex lever 45 in a clockwise direction into the interrupted line position wherein the lower end of the lever is situated directly in the path of the movement of the lower pin 37. Hence if the wheel 34 is released while the duplex lever is in the interrupted line position the lower pin 37 will engage the lower end of the lever and be held against movement until the said lever is restored to initial position, such restoration only occurring when the member 48 returns to its uppermost position and the figure wheel comes to rest. Hence the transfer is withheld until the figure wheel is in proper condition to receive such transfer.

Rotation of the duplex lever on movement of the part 48 is limited by abutment of the lever against a fixed pin 49.

Also means are provided for enabling prevention of a transfer from one wheel to the next when the machine is to be used for the purpose of subtraction. In the example shown the pinion 12 and slotted wheel 38 associated with each figure wheel are secured together to form a unit slidable on the spindle 11, said unit being provided with a radial arm 50 (Figs. 2 and 6) engageable at its outer end in an open ended slot 51 in the peripheral flange of the figure wheel. Also a spring 52 is provided around the spindle 11 between the inner side of the figure wheel and the aforesaid slidable unit, this spring serving normally to hold the slotted wheel in a position wherein it can be engaged by its corresponding pins 37.

Associated with each figure wheel is a button or other finger piece 53 (Figs. 4 and 6) arranged to extend through the casing 54 of the machine so as to be operable from the exterior of the latter, said button being carried on a pivotal arm 55 engaging at its upper end the front end of a longitudinally slidable bar 56. The rear end of the bar 56 is shaped to the form shown in Fig. 6 so as to provide an inclined bearing surface 57 and this end of the bar is arranged in contact with the slotted wheel 38 and between the latter and a frame plate 58 with the bearing surface 57 in contact with an edge 59 of the frame plate.

During a normal transfer operation the slotted wheel is rotated by the pins 37 to revolve the figure wheel through the intermediary of the arm 50. When however the button 53 is pressed inwardly of the casing 54 the bar 56 is moved rearwardly to slide the surface 57 over the edge 59, such movement causing the rear end of the bar to be displaced to move the pinion 12 and slotted wheel 38 along the spindle 11 towards the figure wheel and against the action of the spring 52. Movement of the bar in the manner described is limited by the abutment of a fixed pin 60 against the front end of a slot 61 in the bar and in this limiting position of the bar the slotted wheel is held out of the path of movement of the transfer pins 37. Hence when the button 53 is held depressed no transfer can be transmitted to the figure wheel, the pins 37 moving idly when the wheel 34 is rotated. In the limiting position of the bar 56 the pinion 12 is still however in a position to be engaged and rotated by the rack 13.

When the button 53 is released the parts are returned to initial position by the action of the spring 52.

The invention is not limited to the example above described as subordinate details of construction may be varied to meet different requirements. For example the invention is not limited to a pair of double armed levers 21, 22 and 23, 24 since by suitable alteration of the 2:1 gear ratio more than two of such levers may be employed. In all cases however at least two of such levers are necessary.

I claim:

1. In a calculating machine of the kind referred to the combination of a figure or totalizing wheel spring urged in the direction opposite to that in which it is rotated during normal operation of the machine, a detent associated with said wheel and serving to hold the same against movement in said reverse direction when the wheel is at rest out of zero position, a cam having a fall thereon and rotated by rotation of the wheel, a rotatable stop member, and at least two levers controlled by the cam for arresting the stop member, the arrangement being such that normally the spring serves to urge the stop member into engagement with one of the levers and also to urge the wheel or a part associated therewith against the detent when the wheel is out of zero position, withdrawal of the detent from the wheel or part associated therewith when the wheel is out of zero position permitting the spring to revolve the cam and the wheel in directions opposite to that in which they are rotated during normal operation of the machine, the stop member remaining in engagement with the lever aforementioned and the cam being finally arrested in a position wherein the wheel is in the zero position by engagement of the fall with a lever other than that which is arresting the stop member.

2. A calculating machine including a pair of numeral wheels of successive orders, means for imparting advancing movements to the wheel of lower order, and means for effecting a transfer from said wheel to the wheel of higher order, said transfer means comprising a rotary member operatively associated with the wheel of lower order to make a complete rotation only during a plurality of rotations of said wheel of lower order, spring means arranged to be tensioned when said rotary member is rotated, escapement means maintaining tension in said spring means, and means through which said spring means is arranged to impart transfer movements to the wheel of higher order, said rotary member tripping said escapement means to effect transfer to the wheel of higher order through said spring means and the last mentioned means.

3. A calculating machine including a pair of numeral wheels of successive orders, means for imparting advancing movements to the wheel of lower order, and means for effecting a transfer from said wheel to the wheel of higher order, said transfer means comprising a rotary member operatively associated with the wheel of lower order to make a complete rotation only during a plurality of rotations of said wheel of lower order, spring means arranged to be tensioned when said rotary member is rotated, escapement means maintaining tension in said spring means, and means through which said spring means is arranged to impart transfer movements to the wheel of higher order, said rotary member tripping said escapement means to effect transfer to the wheel of higher order through said spring means and the last mentioned means, said last mentioned means comprising a slotted member

movable with the wheel of higher order and a rotary element provided with a plurality of pins arranged to enter the slots of the slotted member to drive the same.

5. 4. A calculating machine including a pair of numeral wheels of successive orders, means for imparting advancing movements to the wheel of lower order, and means for effecting a transfer from said wheel to the wheel of higher order, 10 said transfer means comprising a rotary member operatively associated with the wheel of lower order to make a complete rotation only during a plurality of rotations of said wheel of lower order, spring means arranged to be tensioned when said rotary member is rotated, escapement means maintaining tension in said spring means, and means through which said spring means is arranged to impart transfer movements to the wheel of higher order, said rotary member tripping said escapement means to effect transfer to the wheel of higher order through said spring means and the last mentioned means, said last 15 mentioned means comprising a slotted member movable with the wheel of higher order and a rotary element provided with a plurality of pins arranged to enter the slots of the slotted member to drive the same, said pins and slots being fitted and related to each other so that at the completion of a driving movement the pins prevent any substantial overrun of the slotted member.

5. A calculating machine including a pair of numeral wheels of successive orders, means for imparting advancing movements to the wheel of lower order, and means for effecting a transfer from said wheel to the wheel of higher order, said transfer means comprising a rotary member operatively associated with the wheel of lower order to make a complete rotation only during a plurality of rotations of said wheel of lower order, spring means arranged to be tensioned when said rotary member is rotated, escapement means maintaining tension in said spring means, and means through which said spring means is arranged to impart transfer movements to the wheel of higher order, said rotary member tripping said escapement means to effect transfer to the wheel of higher order through said spring means and the last mentioned means, said last 20 mentioned means comprising a slotted member movable with the wheel of higher order and a rotary element provided with a plurality of pins arranged to enter the slots of the slotted member to drive the same, said pins and slots being fitted and related to each other so that at the completion of a driving movement the pins prevent any substantial overrun of the slotted member.

5. A calculating machine including a pair of numeral wheels of successive orders, means for imparting advancing movements to the wheel of lower order, and means for effecting a transfer from said wheel to the wheel of higher order, said transfer means comprising a rotary member operatively associated with the wheel of lower order to make a complete rotation only during a plurality of rotations of said wheel of lower order, spring means arranged to be tensioned when said rotary member is rotated, escapement means maintaining tension in said spring means, and means through which said spring means is arranged to impart transfer movements to the wheel of higher order, said rotary member tripping said escapement means to effect transfer to the wheel of higher order through said spring means and the last mentioned means, said last 25 mentioned means comprising a slotted member movable with the wheel of higher order and a rotary element provided with a plurality of pins arranged to enter the slots of the slotted member to drive the same, said pins and slots being fitted and related to each other so that at the completion of a driving movement the pins prevent any substantial overrun of the slotted member.

6. A calculating machine including a pair of numeral wheels of successive orders, means for imparting advancing movements to the wheel of lower order, and means for effecting a transfer from said wheel to the wheel of higher order, the last mentioned means including a driving member provided with a plurality of pins and a driven member provided with slots arranged to receive said pins, the driven member being normally rotatable independently of said driving member, and said pins and slots being fitted and related to each other so that at the completion of driving movements the pins prevent any substantial overrun of the driven member.

7. A calculating machine including a pair of numeral wheels of successive orders, means for imparting advancing movements to the wheel of

lower order, and means for effecting a transfer from said wheel to the wheel of higher order, the last mentioned means including a driving member provided with a plurality of pins and a driven member provided with slots arranged to receive said pins, the driven member being normally rotatable independently of said driving

member, and said pins and slots being fitted and related to each other so that at the completion of driving movements the pins bring said driven member substantially to rest before leaving the slots.

CHRISTOPHER FREDERICK WEBB.
